UNITED STATES PATENT OFFICE

169,017

RAIN CAPE

Viola Street, Denver, Colo.

Application August 30, 1952, Serial No. 21,242

Term of patent 7 years

(Cl. D3—3)

To all whom it may concern:

Be it known that I, Viola Street, a citizen of the United States, residing at Denver, State of Colorado, have invented a new, original, and ornamental Design for a Rain Cape, of which the following is a specification, reference being had to the accompanying drawing, forming a part hereof.

I claim:

The ornamental design for a rain cape, as shown.

VIOLA STREET.
